(57) **CLAIM**

The ornamental design for an LED fixture, as shown and described.

DESCRIPTION

FIG. 1 is a perspective view of an LED fixture according to the present invention, wherein the dotted lines depict a support leg that is not a claimed feature of the present invention.

FIG. 2 is a front elevation view of the LED fixture illustrated in FIG. 1.

FIG. 3 is a rear elevation view of the LED fixture illustrated in FIG. 1.

FIG. 4 is a top plan view of the LED fixture illustrated in FIG. 1.

FIG. 5 is a bottom plan view of the LED fixture illustrated in FIG. 1.

FIG. 6 is a first end elevation view of the LED fixture illustrated in FIG. 1; and,

FIG. 7 is a second end elevation view of the LED fixture illustrated in FIG. 1.
